J. F. FREY,
MEANS FOR PREPARING DRY MATS FOR STEREOTYPING.
APPLICATION FILED MAR. 6, 1914.

JOHN FREMONT FREY, OF INDIANAPOLIS, INDIANA.

MEANS FOR PREPARING DRY MATS FOR STEREOTYPING.

1,162,470.

Specification of Letters Patent.

Patented May 9, 1916.

Original application filed February 28, 1913, Serial No. 750,800. Divided and this application filed March 6, 1914. Serial No. 822,907.

To all whom it may concern:

Be it known that I, John Fremont Frey, a citizen of the United States, residing at Indianapolis, in the county of Marion and State of Indiana, have invented a new and useful Means for Preparing Dry Mats for Stereotyping, of which the following is a specification.

My invention relates to means for preparing matrices for stereotype plates from dry flong mats, and has for its object the betterment of such matrices.

This application is a division of my co-pending application, Serial No. 750,800, filed Feb. 26, 1913.

It has heretofore been considered that clearer stereotype plates may be made from wet mats than from dry mats, because the dry mats as heretofore used were less plastic than the wet mats and in consequence would not so readily conform to the type face or give so great "depth" of impression, besides causing injury to the type in molding. However, the use of wet mats requires a longer time, so that, especially in the rush of getting out a "rush" extra edition of a newspaper, when every second counts, dry mats are much used although they have not heretofore given as goods results as the wet mats. The delay in the use of the wet mats, and an unavoidable delay, is that due to the necessity for the drying of the wet mats on the drying table, and perhaps for heating up the drying table as in the case of an unexpected extra, after the mat has received the type impression.

With my invention, dry mats are made softer and more plastic, so that they take the type impression more readily and accurately and with greater depth, by conditioning them in a special form of humidor which I have devised. By this humidor the dry mats are made humid uniformly, so that they better take the type impression, but they are not made wet and do not require drying on the drying table. After the properly conditioned dry mat has received the type impression, it is only necessary to place it for a few seconds on the scorcher in the same manner as in the case of unconditioned dry mats and of dried wet mats.

The accompanying drawing illustrates my special humidor, for use in my improved method of preparing matrices from dry flong mats.

Figure 1 is a vertical longitudinal section of my humidor, taken substantially on the line 1—1 of Fig. 2, the mat-holding frame being removed; Fig. 2 is a section on the line 2—2 of Fig. 1, the mat-holding frame being in place and holding several mats; Fig. 3 is a section on the line 3—3 of Fig. 1, showing the mat-holding frame in place; Fig. 4 is an isometric view showing the mat-holding frame; Fig. 5 is an isometric view of one of the moisteners of the humidor.

The humidor casing 10 has a cover 11 hinged at 12 and conveniently provided with a hasp 13 whereby it may be fastened in closed position, the casing being substantially air-tight when the cover is closed. On the inner surfaces of the vertical wall of the casing 10 there are provided a number of vertical guideways 14 opening at the top but practically closed at the bottom by a narrow shelf 15. The guideways 14 receive moisteners 16, conveniently in plate form, and made of some material, such as certain kinds of clay, which absorbs water easily but allows it to evaporate readily therefrom. To prevent breakage, the moisteners are suitably bound at their edges in a metal binding 17. The moisteners 16, when in place, are supported on the shelf 15, but project beyond the edges of such shelves so that they may be readily grasped and lifted out of the guideways 14.

A mat-holding frame 20 rests on the floor 21 of the casing 10 and is provided with a reticulated floor 22 spaced above the floor 21. Fastened to the upper surface of the floor 22 are a number of parallel, inverted U-shaped braces 23, conveniently of wire, these braces being spaced from each other to receive the mats 24 to be conditioned. The braces 23 hold the mats 24 apart and in vertical position, so that the humid air within the humidor may circulate on all sides of such mats and condition them uniformly.

In operation, a number of dry flong mats are placed in the spaces between the braces 23 within the casing 10, and the moisteners 16, first having been allowed to absorb a sufficient quantity of water, are placed in the guideways 14. The cover 11 now being closed, the moisteners 16 yield up their moisture to the air within the casing 10, which air circulates on all sides of every mat in the humidor and thoroughly conditions these mats by making them humid, but not wet,

throughout. This humidifying of the mats is entirely uniform. The amount of moisture absorbed by a mat in humidifying is inconsiderable as compared with the amount of moisture in a wet mat.

After having been allowed to remain in the humidor for several hours or longer, and it does not damage mats to remain in the humidor for much longer than that, even 10 several mouths for most types of dry mats, the conditioned or humidified mats are removed from the humidor and molded in the usual manner under pressure on the exposed type face of the forms of type of which 15 stereotype plates are desired. Then the matrices thus formed by the molding of the dry mats are placed for a few seconds on a scorcher, then being removed therefrom and used as molds for casting the stereotype 20 plates desired. The scorcher may be of any suitable type, for there are several well known and successful types. The scorching process consists of applying for a short time to the mats a sufficient degree of heat to 25 drive off the small amount of moisture which is present in humidified dry mats conditioned in my humidor, as well as in wet mats after they have been dried in the drying table especially if exposed to the atmosphere 30 during the time required for preparing them for casting, this degree of heat ordinarily being such that if applied continuously the mat will be charred or burned. Wet mats cannot be applied to the scorcher without 35 preliminary drying, as they would be rendered useless by such application on account of the great amount of moisture they contain and on account of their laminated construction. One well known type of scorcher 40 consists merely of a metal plate, conveniently semi-cylindrical in shape, heated on the concave side by a gas flame, the mat to be scorched being placed on the convex surface for a few seconds, sufficiently long to 45 drive out the moisture, but not sufficiently long to burn or char the mat. By having the mats properly conditioned, the type impression is rendered much clearer and sharper and of greater depth, as are also 50 half-tones and other illustrations, than is the case when unconditioned dry mats are used, and the resultant stereotype plates and prints therefrom are greatly improved. However, the amount of moisture absorbed 55 in the conditioning process of the dry mats is so inconsiderable that it is not necessary to put them on a drying table, as is neces-

sary with a wet mat, in order to avoid the possibility of disastrous effects from the presence of moisture when the stereotype 60 plates are cast. Thus by my invention the time required for producing a clear stereotype plate is very much reduced, especially when there is no drying table in condition for use.

I claim as my invention:

1. A humidor for conditioning dry mats for forming matrices for stereotype plates, comprising a casing, moisteners removably mounted in said casing, and a removable 70 mat-holding frame having a reticulated floor spaced from the floor of the casing and provided with means for holding the mats to be conditioned and spacing them apart.

2. A humidor for conditioning dry mats 75 for forming matrices for stereotype plates, comprising a casing, moisteners removably mounted in said casing, and a mat-holding frame having a reticulated floor spaced from the floor of the casing and provided 80 with means for holding the mats to be conditioned and spacing them apart.

3. A humidor for conditioning dry mats for forming matrices for stereotype plates, comprising a casing, moisteners removably 85 mounted in said casing, and a removable mat-holding frame having a reticulated floor spaced from the floor of the casing and provided with a plurality of parallel braces of inverted U-shape attached to said floor 90 and spaced from each other so that they serve to support in upright position the mats to be conditioned and to space such mats apart.

4. A humidor for conditioning dry mats 95 for forming matrices for stereotype plates, comprising a casing, moisteners removably mounted in said casing, and a mat-holding frame having a reticulated floor spaced from the floor of the casing and provided with a 100 plurality of parallel braces of inverted U-shape attached to said floor and spaced from each other so that they serve to support in upright position the mats to be conditioned and to space such mats apart.

In witness whereof, I have hereunto set my hand at Indianapolis, Indiana, this fourth day of March, A. D. one thousand nine hundred and fourteen.

JOHN FREMONT FREY.
